(57) **CLAIM**

The ornamental design for a loudspeaker waveguide, as shown and described.

DESCRIPTION

FIG. 1 is a top right perspective view of an embodiment of the loudspeaker waveguide, with mounting holes and mounting hole posts being illustrated in dashed lines;

FIG. 2 is a front view thereof;

FIG. 3 is a rear view thereof, with mounting holes, mounting hole posts, and mounting post fins being illustrated in dashed lines;

FIG. 4 is a left side view thereof;

FIG. 5 is a right side view thereof;

FIG. 6 is a top view thereof; and

FIG. 7 is a bottom view thereof.

FIG. 8 is a top right perspective view of another embodiment of the loudspeaker waveguide with mounting holes and mounting hole posts being illustrated in dashed lines;

FIG. 9 is a front view thereof;

FIG. 10 is a rear view thereof, with mounting holes, mounting hole posts, and mounting post fins being illustrated in dashed lines;

FIG. 11 is a left side view thereof;

FIG. 12 is a right side view thereof;

FIG. 13 is a top view thereof; and,

FIG. 14 is a bottom view thereof.

The dash lines indicate unclaimed portions and form no part of the claimed design.
